UNITED STATES PATENT OFFICE.

LUCIEN ANDUZE, OF LIMOGES, FRANCE, ASSIGNOR TO HERMAN C. KUPPER, OF NEW YORK, N. Y.

DESIGN FOR A TEAPOT OR SIMILAR ARTICLE.

Application filed October 28, 1921. Serial No. 511,152. Term of patent 14 years.

To all whom it may concern:

Be it known that I, LUCIEN ANDUZE, a citizen of the Republic of France, residing at the city of Limoges, in the Department of Hautevienne, France, have invented a new, original, and ornamental Design for a Teapot or Similar Article, of which the following is a specification, reference being had to the accompanying drawing, forming part thereof.

Fig. 1 is a side view; and
Fig. 2 is a front view of a teapot illustrating my new design.

I claim:

The ornamental design for a teapot or similar article as shown.

Signed at the city of Limoges, Department of Hautevienne, France, this 6th day of October, 1921.

LUCIEN ANDUZE.
